UNITED STATES PATENT OFFICE.

MARTIN RICHARD DRISCOLL, OF FRISCO, UTAH.

SCREEN FOR STAMP-MILLS.

SPECIFICATION forming part of Letters Patent No. 656,098, dated August 14, 1900.

Application filed October 20, 1899. Serial No. 734,275. (No model.)

To all whom it may concern:

Be it known that I, MARTIN RICHARD DRISCOLL, of Frisco, in the county of Beaver and State of Utah, have invented a new and Improved Screen for Stamp-Mills, of which the following is a full, clear, and exact description.

The invention relates to screens for stamp-mills such as shown and described in the Letters Patent of the United States No. 629,242, granted to me on July 18, 1899.

The object of the present invention is to provide a new and improved screen for stamp-mills arranged to permit of conveniently changing a wire screen-cloth without stopping the battery and securely holding the screen-cloth in position while the battery is in use.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a front elevation of the improvement as applied. Fig. 2 is a sectional plan view of the same on the line 2 2 in Fig. 3 and with the extended portion of one roll of screen-cloth clamped in position and the other held loosely over the discharge-opening. Fig. 3 is a sectional plan view of the improvement on the line 3 3 in Fig. 1 and 35 with the screen-cloth-clamping frames removed. Fig. 4 is a rear face view of the improvement with one gate and screen-cloth removed. Fig. 5 is a transverse section of the improvement on the line 5 5 in Fig. 1. Fig. 40 6 is an enlarged end elevation of the roll of screen-cloth and its support, and Fig. 7 is an enlarged cross-section of the clamping device for the lower end of the screen.

On the front A of the stamp-mill frame or 45 mortar is arranged an outlet-opening A', and adjacent to the latter are formed recesses for receiving a skeleton frame B, the front face of which is flush with the front A and which skeleton frame is formed in its lower portion 50 with openings B' B², registering with the opening A' and through which passes the screened material. The openings B' B² are

separated by a vertical partition B³, in the sides of which are formed guideways B⁴, and similar guideways B⁵ are arranged near the 55 sides of the frame B, at the rear face thereof, to fit upon the side walls of the opening A, as is plainly indicated in Figs. 2 and 3.

In the guideways B⁴ and B⁵ are mounted to slide the gates C C' for opening or closing 60 the discharge-openings B' B², respectively, said gates being provided with upwardly-extending rods C², passing through a slot in the roof of the frame or mortar A and provided with apertures C³, one of which is engaged 65 at a time by a transverse pin C⁴, adapted to rest on the upper edge of the top of the front A and the upper edge of the frame B to hold the gate in the desired position—that is, more or less open, according to the desired amount 70 of discharge of the material from the stamp-mill.

The openings B' B² are adapted to be covered at the front of the frame B by the extended screen-cloth portions D² D³, unwound 75 from the rolls of screen-cloth D D', each having its reel or core formed at the ends with toothed journals D⁴, engaging teeth E' on the horizontal members of the brackets E, bolted or otherwise fastened to the front face of the 80 frame B, as illustrated in Figs. 1 and 6. By the arrangement described the rolls D D' can be adjusted transversely to bring the rear end of the roll in firm contact with the front face of the frame B at a distance above the openings B' and B², and at the same time the rolls 85 are held against accidental unwinding of the screen-cloth when the stamp-mill is in use and the material in the mill exerts pressure against the inner face of the extended portion D² or D³. Furthermore, the operator is enabled to turn the roll so as to draw the extended portion tight in a vertical direction by turning the roll correspondingly in its 90 bearings. By the teeth of the roll and the 95 bracket meshing, as described, the roll is held from unwinding, and at the same time the roll can be transversely adjusted, so that when the roll becomes less in diameter upon using the screen-cloth it can be readily moved 100 rearwardly to at all times hold the rear part of the roll against the face of the frame B.

In order to clamp the extended portions D² D³ of the screen-cloth in position on the frame

B over the openings B' B², I provide two rectangular frames F F', arranged to engage the screen-cloth at the sides, top, and bottom portions, the lower edge of the screen-cloth passing around the lower bar of a clamping-frame to be then clamped to this bar by auxiliary clamping-bars G G', held transversely adjustable on bolts H, attached to the frame B. The clamping-frames F F' have their openings approximately of the size of the openings B' B², and the outer side bars of the said frames are formed with vertical slots F², engaged by bolts I, held on the frame B. The inner adjacent bars of the said frames F F' are simultaneously engaged by clamping-bolts I', held on the partition B³.

Now by the arrangement described the bolts I I' simultaneously fasten the frames F F' in position; but when it is desired to adjust one of the extended portions of the screen-cloth then it is necessary to loosen the corresponding frame by loosening the bolts I I', and in order to hold the other clamping-frame temporarily in position when the bolts I' are loosened I provide a crank-screw J, held on the partition B³ and adapted to engage either of the frames F or F' at the inner end, as indicated in Figs. 1 and 2. For instance, when it is desired to adjust the screen portion D² the bolts I and H for the clamping-frame F are loosened, and before loosening the bolts I' the crank-screw J is engaged with the frame F', so as to hold the latter in place when the bolts I' are loosened to allow of drawing the screen-cloth portion D² downward for swinging a new portion of the screen-cloth over the opening B'.

In order to hold the lower auxiliary clamping-bar G or G' in proper position relatively to the corresponding clamping-frame F or F', I provide each of the said bars G G' with inwardly-extending lugs G³, adapted to rest against the front face of the frame B when the bar is in an innermost clamping position, as indicated in Figs. 5 and 7.

When the stamp-mill is in use, the gates C C' are held in an open position to permit the fine particles of material reduced to the desired size to pass through the screen-cloth portions D² D³, and when it is desired to remove one of the worn-out screen-cloth portions D² or D³ then the corresponding gate C or C' is closed to shut off the material from the screen-cloth portion. The bolts I, I', and H are then loosened, as previously described, while the other frame is temporarily engaged and clamped at its inner end by the crank-screw J, and then the operator raises the clamping-frame F and draws the screen downward until sufficiently removed, and then the clamping-frame F is lowered to its former position, with the screen between its bottom edge and the bolts H. The bottom portion of the screen is then doubled up over the outer face of the bottom bar of the clamping-frame F and is clamped in this position by the auxiliary bar upon screwing up the

bolts H. The screen is then nicely stretched by turning the reel up a notch or two, after which the bolts I I' are screwed up, and then the gate is raised and the worn-out portion torn off. Thus it will be seen that it is not necessary to completely stop the battery or take out the entire frame B while changing the screen-cloth to remove the worn-out portion and replace it by a new unused cloth. By having two screen-cloths, as described, the operator can change one while the other is in use.

Having thus fully described my invention, I claim as new and desire to secure by Letters Patent—

1. A screen for stamp-mills, comprising an apertured frame, a roll of screen-cloth mounted above the aperture and having a portion of the cloth extending over the aperture, the said roll being adjustable to bring the roll in firm contact with the front face of the apertured frame, a rectangular clamping-frame for clamping the cloth to the sides top and bottom of the aperture, bolts for adjustably holding the clamping-frame in place on the apertured frame, and an auxiliary clamping-bar on the apertured frame for clamping the lower end of the cloth upon the front face of the bottom bar for the rectangular clamping-frame, substantially as shown and described. 85

2. A screen for stamp-mills, comprising an apertured frame, a roll of screen-cloth mounted above the aperture, and having a portion of the cloth extending over the aperture, the roll being transversely adjustable, to bring the rear part thereof flush with the face of said apertured frame and means for clamping the cloth to the frame, substantially as 95 shown and described.

3. A screen for stamp-mills, comprising an apertured frame, a roll of screen-cloth mounted above the aperture, and having a portion of the cloth extending over the aperture, the roll being transversely adjustable, to bring the rear part thereof flush with the face of said apertured frame, means for locking the roll against accidental unwinding of the cloth and permitting of stretching the extended portion and means for clamping the cloth to the frame, substantially as shown and described. 110

4. A screen for stamp-mills, comprising a frame having a plurality of apertures, a plurality of separate clamping-frames for the screen to hold the latter in front of the openings, a single row of bolts for clamping the adjacent inner ends of said frames in position, a row of bolts for each outer end of a clamping-frame, and a device carried by the apertured frame for temporarily engaging and holding the inner end of either of said clamping-frames, substantially as shown and described. 120

5. A screen for stamp-mills, comprising a frame having a plurality of apertures, rolls of screen-cloth mounted above the apertures, and having portions of the cloth extending

above the apertures, a plurality of separate clamping-frames for said extended portions of the screen-cloth, a single row of bolts for clamping the adjacent inner ends of said frames in position, a row of bolts for each outer end of a clamping-frame, and a crank-screw on the apertured frame, and arranged for temporarily engaging the inner end of either of said clamping-frames, substantially as shown and described.

6. A screen for stamp-mills, provided with a screen-cloth roll having toothed journals at the ends, and supports for said roll, and having toothed transverse members adapted to be engaged by the toothed journals, substantially as shown and described.

7. The combination with the apertured frame on the front of the stamp-mill or mortar, of a roll of screen-cloth mounted above the aperture, means for adjusting said roll to bring its rear face flush with the face of the

apertured frame, a rectangular clamping-frame to hold the screen-cloth in front of the aperture, means for adjusting the clamping-frame, and an auxiliary clamping-bar for the lower end of the screen-cloth, substantially as described.

8. The combination with the apertured skeleton frame on the front of the stamp-mill or mortar, of a plurality of clamping-frames for the screen, to hold the latter in front of the skeleton-frame openings, clamping-bolts for engaging the side bars of the said frames, the bolts for the adjacent side bars simultaneously engaging the latter, and a clamping-bolt on the said skeleton frame, and adapted to engage either of the said clamping-frames, substantially as shown and described.
